Fig. 4.

FIG. 1 is a side elevational view of an electric fan or similar article, showing my new design in suspended operational position.

FIG. 2 is a fragmentary top plan view.

FIG. 3 is a bottom plan view.

FIG. 4 is a cross-sectional view, to an enlarged scale, taken diametrically through the outer casing but showing the motor and fan assembly in side elevation.

FIG. 5 is a perspective view thereof, to a reduced scale, in side operational position.

The fragmentary portion of a table shown in broken lines in FIG. 5 is for illustrative purposes only. The dominant features of my new design are shown in solid lines in the drawing.

This application is a continuation-in-part of my application, Serial Number D. 51,798, filed July 15, 1958, now abandoned.

I claim:

The ornamental design for an electric fan or similar article as shown and described.
